DOOR LATCH

Charles S. Comey and Millard F. Saxton, Flint,
Mich., assignors to The Engineered Products
Company, Flint, Mich., a corporation of Michigan

Application December 14, 1949, Serial No. 132,935

1 Claim. (Cl. 70—129)

1

This invention relates to a rim latch for a door and particularly to a latch of the type commonly used for screen doors and similar applications.

Screen door latches as commonly constructed are usually provided with a dead bolt arrangement which is mounted on the inner trim plate for the latch and operable from the inner side of the door but not from the outer side of the door. With latches of this type, it is impossible to leave the premises with the door to the premises open and with the screen door locked from the outer side of the door. The provision of a latch which enables a screen door to be locked and unlocked from the outside as well as the inside is for obvious reasons very desirable.

It is accordingly an object of this invention to provide a rim type latch for a door which is of simple construction and therefore economical to manufacture and which is provided with a dead bolt arrangement which can be operated manually from the inner side of the door and by means of a key from the outer side of the door.

More specifically, the invention contemplates a latch which includes inner and outer trim plates adapted to be mounted on opposite sides of a door, one of the trim plates, preferably the inner, forming a housing for a latch bolt assembly and carrying a dead bolt arrangement. The other trim plate is provided with a member which telescopically engages a spindle on the inner trim plate for operating the dead bolt by means of a key from the outer side of the door. The telescoping members for the inner and outer trim plates are of substantial length and enable the latch to be mounted on different doors which vary considerably in thickness.

Other objects and improvements in the nature of the simplicity of construction and the provision of a dead bolt assembly integral with one of the trim plates will become apparent from the following description and drawings in which:

Figure 1 is a perspective view of the latch of this invention.

Figure 2 is a plan view of the latch assembly from the inner trim plate side thereof.

Figure 3 is a plan view of the latch assembly from the outer trim plate side thereof.

Figure 4 is a perspective view of the striker plate.

Figure 5 is a plan view of the inside of the inner trim plate.

Figure 6 is a sectional view taken along lines 55

6—6 in Figure 1 with the latch mounted on a door and with the latch bolt assembly removed.

Figure 7 is a perspective view of the dead bolt mechanism.

5 Figure 8 shows a key which may be utilized for operating the dead bolt from the outside of a door.

Figure 9 is a perspective view of the latch bolt mechanism.

10 Figure 10 is a sectional view taken along lines 10—10 in Figure 5.

Referring to the drawings, there is shown an inside trim plate and latch assembly housing 10 having a recess 12 which is adapted to receive a latch bolt assembly 14. The housing 10 has mounted thereon a stub spindle 16 of non-circular shape which carries the usual handle 18 at its outer end.

The outside trim member comprises an escutcheon plate 20 having a spindle 22 of non-circular form rotatably secured thereto and carrying a handle 24 at its outer end.

The latch assembly 14 is identical with the latch assembly shown in co-pending application 697,865 filed September 19, 1946, now Patent No. 2,554,438, dated May 22, 1951, and comprises a frame 26 which seats freely within recess 12 of housing 10. Frame 26 rotatably supports a cam member 28 having a cam surface 30 which is engaged by a follower 32 formed integrally with a latch bolt 34 pivoted on frame 26 as at 36. A light coil spring 38 acts between latch bolt 34 and frame 26 to bias follower 32 into engagement with the operating surface 30 of cam 28. A heavy coil spring 40 is mounted within cam 28 and serves to center the cam so that latch bolt 34 is normally in the projected position shown in Figures 1, 3, and 9. Cam 28 is also provided with a central socket 41 of non-circular shape extending through the cam which, when the latch bolt assembly 14 is seated within recess 12, is arranged to receive the ends of spindles 16 and 22. When either handle 18 or 24 is turned, cam 28 is rotated and causes follower 32 to ride up the operating surface 30 of the cam and thereby retract latch bolt 34.

The arrangement thus far described is identical in both construction and operation with that shown in our above-mentioned co-pending application. The particular latch bolt assembly 14 has been described only for the purposes of illustration and it will become apparent that latch bolt assemblies other than that shown

may be employed without departing from the present invention.

The feature of the latch which we believe to be an improvement over the latch shown in said co-pending application resides in the provision of a dead bolt locking arrangement which is operable either manually from the inside of the door or by means of a key from the outside of the door. This arrangement includes a dead bolt 42 which projects through an opening 43 on the front wall of housing 10. To the rear end of bolt 42 there is riveted a carrier 44. Housing 14 is preferably formed as a sheet metal stamping and is fashioned with a shoulder 46 which is provided with an elongated slot 48. A long knob 50 is slidably arranged on the outer face of shoulder 46 overlying carrier 44. Knob 50 is connected with carrier 44 by a pin 52 which extends through slot 48 and is riveted on carrier 44 as at 54. A leaf spring 56 is arranged between the inner face of shoulder 46 and a flat portion 58 of carrier 44. Spring 56 has projections 60 formed at each end thereof which frictionally engage the inner face of shoulder 46 and thereby provide sufficient drag on carrier 44 to prevent bolt 42 from becoming jarred from either the projected or retracted position. Spring 56 serves to maintain bolt 42 in the position to which it is positively actuated.

At the upper and lower edges, housing 10 is 30 fashioned with flat attaching flanges 62 and 64 which are apertured as at 66 so as to permit the housing to be attached to the face of a door by means of screws. On the inner face of flange 62, there is supported a strap member 68. Strap 68 is preferably secured to flange 62 by peening over the inwardly drawn metal around the screw holes as at 70 (Figure 10). Strap 68 is fashioned with an inwardly offset portion 72 between the outer face of which and the inner face of flange 62 there is arranged a yoke member 74. Yoke 74 is pivoted to the housing by a spindle 76 which extends through the offset portions 72 of strap 68 and is riveted to yoke 74. The free end of yoke 74 slidably engages a pin 78 fixed to the rear end of carrier 44.

The outer escutcheon plate 20 is apertured as at 80, the aperture being covered by a rotatable disc 82 which is slotted as at 84 to receive a key 86. On the inner face of plate 20, there is mounted in alignment with slot 84, a cylindrical sleeve 88 which is arranged to telescope over spindle 76 when the inner and outer plates are mounted on opposite sides of a door. Spindle 76 is provided with suitable slots 90 with which corresponding formations 92 on key 86 are adapted to engage so as to rotate spindle 76 when the key is turned.

To mount our latch on a door, such as is illustrated at 91, it is only necessary to drill two holes in the door as at 94 and 96. Hole 94 is of a size to accommodate spindle 22 and hole 96 accommodates sleeve 88. These holes are spaced apart corresponding to the spacing of spindle 22 and sleeve 88. Escutcheon plate 20 is secured to the outer face of the door by screws driven through openings 98. Before securing housing 10 to the inner face of the door, latch bolt assembly 14 is seated in recess 12 with the pivoted bolt 34 projecting through the opening 99 formed in the front wall of housing 10. It will be appreciated, of course, that before latch assembly 14 can be inserted in recess 12, the non-circular spindle 16 must be arranged to

register with the non-circular opening 41 in cam 28. After latch assembly 14 is seated within recess 12, handle 24 is turned to align spindle 22 with opening 41 on cam 28 and the plates are adjusted so that spindle 76 registers with sleeve 88. When these members are aligned, housing 10 may be pushed against the face of the door and secured thereto by screws passing through openings 66.

10 After housing 14 and plate 20 are secured to the door a suitable striker plate 100 is secured to the door frame. Striker 100 has a pair of openings 102 and 104 therein for receiving bolts 34 and 42 respectively.

15 When it is desired to lock the door from the inside by means of dead bolt 42, knob 50 is merely pushed to the right as viewed in Figure 2 so as to project bolt 42 into openings 104. The turning of handles 18 or 24 will then be ineffective to release the door from the lock position. Bolt 42 can be retracted from the inside by merely sliding knob 50 to the left or from the outside by inserting key 86 in slot 84 and turning in a direction to retract bolt 42. In the arrangement shown, if key 86 is inserted through slot 84 so as to engage the formations 92 with the grooves 90 in spindle 76 and the key is turned in a counter-clockwise direction as viewed in Figure 5, yoke 74 is rotated counter-clockwise and, by reason of its connection with carrier 44 through pin 78, shifts carrier 44 to the left, thereby retracting bolt 42 from opening 104 in the striker plate 100.

20 It will be observed that the arrangement described is adapted for installation on doors of different thicknesses. This is possible because of the telescoping construction of sleeve 88 in spindle 76 and a corresponding telescopic construction between spindle 22 of handle 24 and cam 28. It will also be observed that the dead bolt arrangement is mounted permanently on housing 10 by the simple expedient of strap 72 which overlies yoke 74 and pin 52 which positions carrier 44 and knob 50 on the inner and outer faces of the housing.

25 It will thus be seen that I have provided a dead bolt locking arrangement for a rim type door latch which may be constructed economically and which is very reliable in its operation. The dead bolt assembly is furthermore attached permanently to the housing for the latch assembly and therefore makes for easy installation. The telescoping sleeve and spindle arrangement for the dead bolt permits the latch to be mounted on doors of various thicknesses and enables operation of the dead bolt either manually from the inside of the door or by means of a key from the outside of a door.

We claim:

30 In a rim latch for a door of the type having inner and outer trim plates, the inner of which forms a housing for a latch mechanism, the combination of a dead bolt slidably mounted on the inner face of said inner trim plate, said inner trim plate defining a housing having a front wall, end walls, side walls and a substantially open rear side which is adapted to be closed by the face of the door on which the inner trim plate is adapted to be mounted, said dead bolt being mounted on said inner trim plate for sliding movement from a position lying wholly within said inner trim plate to a position projecting outwardly through an end wall of said trim plate, a knob slidable on the outer face of said inner trim plate, a pin 35 passing through said inner trim plate and con-

necting said knob with said dead bolt, said pin serving to retain said knob and dead bolt on opposite sides of a wall of said inner trim plate, a yoke member lying wholly within the confines of said inner trim plate and having at one end thereof a sliding pivotal connection with said dead bolt, the opposite end of said yoke having a spindle fixedly secured thereto, said spindle projecting outwardly of said inner trim plate substantially beyond and in a direction normal to the plane of said open rear side, a strap secured to the inner face of the front wall of said inner trim plate, said strap having an opening therein in which said spindle is rotatably supported, said yoke lying between said strap and the inner face of said front wall, said outer trim plate having a sleeve thereon which projects normal to and outwardly beyond the face of said outer trim plate which is adapted to be positioned against the face of a door, said sleeve having a telescopic engagement with the free end portion of said spindle, said free end portion of said spindle being rotatable within said sleeve and being fashioned for interengagement with a key inserted through said

5 sleeve from the outer face of said outer trim plate.
